FIG. II.

UNITED STATES PATENT OFFICE

2,487,810

PIVOTED BENDER WITH PIVOTED
SLIDING SIDE SHAPERS

Everett M. Hunt, Portsmouth, N. H.

Application July 13, 1945, Serial No. 604,947

9 Claims. (Cl. 153—11)

(Granted under the act of March 3, 1883, as
amended April 30, 1928; 370 O. G. 757)

1

My invention relates to a forming machine. It has to do, more particularly, with a machine which is especially useful in the formation of a metal pan of square or rectangular shape, although it is not necessarily limited thereto.

In producing square or rectangular pans from sheet metal according to the process which I employ, one of the forming operations consists in bending a partially formed metal blank to form the endwalls of the pan. This blank has previously had its sidewalls formed by suitable forming operations. When the endwalls of the pan blank are formed, a tab is produced at each corner, at the junction of the sidewall and endwall, and this tab projects outwardly diagonally from the corner. It is desirable to bend each tab into alignment with the corresponding sidewall of the pan to facilitate subsequent forming operations on the pan.

The object of my invention is to provide a simple machine which is very effective to form the endwalls of a pan blank for a square or rectangular pan, which has had its sidewalls previously formed, and to bend the diagonally extending tabs, formed as a result of forming the endwalls, into alignment with the sidewalls.

The preferred embodiment of my invention is illustrated in the accompanying drawings wherein similar characters of reference designate corresponding parts and wherein:

Fig. 1 is a front elevational view of a machine constructed according to my invention.

Fig. 2 is a side elevational view, partly broken away, of the machine shown in Fig. 1.

Fig. 3 is a top plan view, partly broken away, of my machine.

Fig. 4 is a vertical sectional view taken substantially along line 4—4 of Fig. 3.

Fig. 5 is a detail, in perspective, of the structure for lifting the pan from the forming means.

Fig. 6 is a detail, in plan, of one of the roll units which bends the tab formed at the corner of the pan.

Fig. 7 is a view similar to Fig. 6 but showing the tab after it has been bent by the roll.

Fig. 8 is a side elevational view of the operating pedal and associated parts of the machine.

Fig. 9 is a perspective view of a portion of a pan blank showing it before it has been subjected to my machine.

Fig. 10 is a view similar to Fig. 9 but showing the blank after the end is bent and the tab is formed by my machine.

Fig. 11 is a view similar to Fig. 10 but showing the pan blank after the tab has been bent into

2

alignment with the sidewall of the blank by my machine.

With reference to the drawings, Fig. 9 shows the pan blank 1 in the form that it is received by my machine. It has sidewalls 2 already formed with the exception of the upper edges thereof which are to be subsequently bent around a reinforcing wire. In forming each sidewall 2, the ends thereof are bent or flared slightly outwardly as indicated at 3.

The blank 1 is to be bent by my machine along the dotted line indicated in Fig. 9. In bending the end of the blank along the dotted line, the endwall 4 (Fig. 10) is formed and simultaneously the portion 3 is bent at the midpoint, indicated by the dotted line in Fig. 9, to form the tab 3a, as shown in Fig. 10, which will extend diagonally outwardly from the corner of the pan blank. The tab 3a will be outwardly formed merely by bending up the end of the blank to form the endwall 4. After the endwalls 4 are formed, it is desirable to bend each of the tabs 3a into the same plane as its corresponding sidewall 2. The pan blank, in the form that it has when it leaves my machine, is shown in Fig. 11 where it will be noted that the tab 3b is in the plane of the sidewall 2. This facilitates subsequent forming operations on the pan blank.

The machine which receives the blank illustrated in Fig. 9 and produces the blank illustrated in Fig. 11 is shown in its general structure in Figs. 1 to 3. It comprises a table 5 that carries the forming units of my machine and which consist of a metal brake or endwall forming unit 6, which forms the endwalls 4, and a pair of forming roll units 7, which operate on the tab 3a.

The endwall forming unit 6 is disposed at the front edge of the table 5. It includes a transversely extending plate 8 which is set on its edge at the forward edge of the top plate 9 (Fig. 4) of the table 5. The plate 8 is removably secured to plate 9 in a suitable manner, such as by metal straps 10, which may be welded to plate 11 and bolted to plate 8 by removable bolts 14. The plate 11 is a supporting plate depending from plate 9 and in the same plane as the plate 8 (Figs. 1 and 4), and also may have its upper edge welded to plate 9. The plate 11 has rearwardly extending bracing plates 12 (Figs. 1, 2 and 4) welded to its side edges and to the undersurface of the plate 9. A second plate 13 (Fig. 4) similar to the plate 8 and of substantially the same size is fastened by means of the removable bolts 14 behind the plate 8.

The plates 8 and 13 are properly spaced by

means of a spacer plate 15, secured in position by the bolts 14 between the lower portions of the plates, which will be of a thickness substantially corresponding to that of the metal of the pan blank. Thus, there is produced a slot 16 between the upper portions of plates 8 and 13 for receiving the ends of the pan blank 1 to be formed. The spacer 15 may be easily removed and replaced with a spacer of different thickness to correspond to that of the metal of various pan blanks to be formed by my machine. The plates 8 and 13 will be of a length corresponding to the distance between the sidewalls 2 of the pan blank 1.

Secured in contact with the rear surface of plate 13 by the bolts 14, is the vertical section 17 of a pan blank supporting member 18. The member 18 has a supporting plate section 19 which extends rearwardly and upwardly from the upper edge of the vertical section 17. The section 17 extends to the same height as plates 8 and 13. The section 19 has its edges tapering towards each other, as shown in Fig. 3. The member 18 has the reinforcing flanges 20 formed thereon and which extend from the edges of both the sections 17 and 19.

A movable forming plate 21 is hinged along one edge to the upper edge of plate 8 by hinges 22. The plate 21 may be swung from a position where it is superimposed on section 19 of member 18, indicated in Fig. 4, to a position where it is substantially vertically disposed, as shown in Figs. 1 and 2.

For moving the plate 21, I provide an arm 23 (Fig. 4). This arm is rigidly connected by a pin structure 24 to the plate 21. The pin structure 24 is substantially perpendicular to plate 21 and the arm 23 extends at an angle from the pin structure. The end of the arm 23 is pivotally connected, as at 25, to the upper end of a piston rod 26 which extends from a cylinder and piston unit 27.

The unit 27 is supported for swinging movement in a vertical plane at right angles to supporting plate 11 by having its lower end pivotally connected, as at 28, to the forward side of plate 11 at its lower end. It will be apparent that actuation of unit 27 will swing plate 21 between its two positions. A fluid line 29 leads from the upper end of unit 27 while a fluid line 30 leads from the lower end of unit 27. These lines are connected to a suitable control valve 31 (Fig. 1) which is connected by a line 32 to a source of fluid under pressure.

In bending the ends of the pan blank 1, the blank, in the condition shown in Fig. 9, is placed on the machine with its end to be bent inserted in the slot 16 between plates 8 and 13. Movement of the end into the slot to a sufficient extent will be permitted due to the outwardly flared portions 3. However, when the plate 13 is reached by the main part of the sidewalls 2, movement into the slot will be stopped. The plate 21 will be in its vertical position, and the blank 1 will be vertical as shown by the dotted lines in Fig. 4. The plate 21 is now actuated by unit 27 so that it will swing rearwardly into the position shown in Fig. 4 and will bend the blank down into contact with the supporting member 18. The section 19 of member 18 is inclined so that the endwall 4 thus formed will be at a desired angle relative to the bottom of the blank. As the endwall 4 is thus formed, the diagonally projecting tab 3a (Fig. 10) is also produced. The pan blank may be removed and its other end formed in a similar manner. It will be noted from Fig. 4 that the sidewall of the

pan blank will be accurately formed and located since it is bent over the upper edge of plate 13 and since the edge of the bending plate 21 lies closely adjacent the upper edge of plate 13. The member 18, plate 21, and the plates 8 and 13, may be replaced with similar members of different lengths to correspond to the widths of various pan blanks formed by my machine.

As previously indicated, when the end of the pan is formed, the diagonal tab 3a is produced. My machine will bend the tab 3a (Fig. 10) to produce the straight tab 3b (Fig. 11). This tab bending operation is performed on each end of the blank by my machine immediately after each endwall is formed and before removing the blank from support 18 and reversing it. This is accomplished by the forming roll units 7.

Each of the roll units 7 consists of a track-supporting bracket 33 (Fig. 1) which is adjustably mounted by means of a bolt and slot connection 34 (Fig. 3) on the top surface of the plate 9. The bracket 33 is thus supported adjacent the side edge of plate but may be adjusted in and out relative to the center thereof. The bracket 33 consists of two upstanding spaced supports which are straddled by the outer spaced portions of a track unit 35. Pivot bolts 33a connect the units 33 and 35. The unit 35 may be adjusted in a vertical plane about the pivots 33a and may be clamped in any desired adjusted position by tightening the pivot bolts 33a.

The inner side of each unit 35 has a pair of identical tracks 36 formed at its upper and lower sides. Each of the tracks 36 is of the shape which is shown best in Figs. 6 and 7. It includes a forward straight edge 37 and a rear laterally extending edge 38 which extends outwardly towards the outer side of unit 35. A hook portion 39 is formed on track 36 behind the laterally extending edge 38.

A rotatable forming roll 40 is associated with each of the units 35. This roll 40 is of fairly large diameter and is of such length that it just fits between the vertically spaced tracks 36. It is carried by a spindle or axle 41 which projects from each end thereof and the projecting portions of which operate along the edges of the tracks 36. The axle 41 is carried on the forward ends of a pair of vertically spaced links 42 (Figs. 2 and 3). The rear ends of the links 42 are held in spaced relationship by a spacer pin 43 upon which the links are pivoted for swinging movement. Each pin 43 is connected by a pivot connection 44 (Fig. 7) to the forward end of a rod 45 so as to permit swinging of pin 43 about the rod 45 in a vertical plane. The rod 45 is spaced outwardly of the edges of tracks 36 and to maintain the axle 41 in contact with the tracks, a spring 46 is associated with the pin 43 and links 42 and tends to swing the links outwardly about pin 43. Thus, the axle 41 is maintained in resilient contact with the tracks 36.

Each rod 45 extends rearwardly of the table and is reciprocably mounted in a bearing sleeve 47 as shown in Figs. 2, 3, 6, and 7. This sleeve is carried by an upstanding support which has a guide 48 on its lower end which fits into a transverse guideway 49 carried on the upper surface of the plate 9. Thus, the bearing sleeves 47 may be adjusted laterally. The guides 48 may be clamped in adjusted position by the clamping strips 50 associated with and forming a part of the guideway. The rear end of each rod 45 is pivoted, as at 51, (Figs. 2 and 3) to the forward end of a link 52. This link 52 has its rear end

pivoted, as at 53, to the upper end of a crankarm 54.

The crankarm 54 is splined for axial movement on a transverse shaft 55 which is rotatably mounted in bearing brackets 56 that are secured to plate 9 at its rear edge. The shaft 55 is rocked by means of a lever 57 that has its upper end keyed thereon and its lower end pivotally connected, as at 58, to the rear end of a piston rod 59. This rod 59 extends rearwardly from a cylinder and piston unit 60. The unit 60 is pivotally connected at its forward end, for movement in a vertical plane, as at 61, to the rear surface of plate 11. A fluid line 62 (Fig. 2) leads from the rear end of unit 60 and a fluid line 63 leads from the forward end of the unit. These two lines connect to a control valve 64 which is connected by a line 65 to a source of fluid under pressure.

It will be noted in Figs. 6 and 7 that the end of the plate 8 is provided with a flange 8a which has a flat outer forming surface. The forming rolls 40 are adapted to roll the tabs 3a (Fig. 10) into contact with these flanges. It will be noted from Fig. 1 that these flanges 8a are disposed at an angle. This angle corresponds to the angle of the sidewalls 2 of the pan blank. If blanks which have sidewalls disposed at a different angle are to be formed on my machine, the plate 8 is replaced with one having flanges 8a disposed at the corresponding angle.

The forming rolls 40 are disposed at the proper angle depending on that of the sidewalls 2 of the pan blank. This angle may be changed by adjustment of brackets 35 about the pivots 33a. This will change the positions of tracks 36. The rolls 40 will be correspondingly tilted by movement of their supporting structures about pivots 44 and they will be maintained in contact with tracks 36 by springs 46. The tracks 36 for the rolls 40 may be adjusted towards and away from each other by adjusting the brackets 33. The rolls 43 may be similarly adjusted by lateral adjustment of members 48 and associated parts. Thus, proper adjustments may be made to permit the machine to operate upon pan blanks of various widths.

Each of the rolls 40 is normally in the position indicated in Fig. 6. If the unit 60 is actuated so that piston rod 59 will be forced rearwardly, a forward push is exerted on the rods 45 and is transmitted to links 42. This pushes the rolls 40 forwardly. The axles 41 move along the angular edges 38 of the tracks 36, rearwardly towards the sidewalls of the pan, and then along the straight edges 37 of the tracks. The rollers eventually reach the tabs 3a and are of such diameter that they bend the tabs 3a against the surfaces of the flanges 8a, as they roll over the tabs, as shown in Fig. 7. Thus, the straight tabs 3b will be produced, as indicated in Fig. 11. When the unit 60 is actuated to move the piston rod 59 forwardly, the rolls 40 will be pulled from the position indicated in Fig. 7 to the position indicated in Fig. 6. The axles 41 will move along the straight edges 37 of the tracks 36 until they reach the outwardly directed edges 38 and then will move outwardly, this action being insured by hook portions 39. Thus, the forming rolls 40 will be moved away from the sides of the pan blank.

The pan blank 1 may have both of its endwalls formed in the manner indicated and the tabs at each end straightened in the manner indicated. To facilitate removal of the pan blank from the

support 18 after each end is formed, I provide the structure illustrated best in Figs. 3 and 5.

This structure comprises a rod 66 which carries a small block 67 at each end thereof and which is adapted to engage the edge of the adjacent sidewall 2 of the pan blank. The rod 66 is carried by a sleeve 68 in which it is removably secured. This sleeve 68 has lugs which are pivoted to a lug, as indicated at 69 that is carried by a sleeve 70. The sleeve 70 is slidably carried on one arm of a crank 71. The crank 71 is rotatably mounted in a bearing sleeve 72 secured to the upper surface of the plate 9. It will be apparent that by rotating crank 71, the rod 66 will be lifted and, consequently, the pan blank will be lifted from the support 18 and this will facilitate its removal.

The valves 31 and 64 are operated at properly timed intervals so that the end forming unit 6 will operate first and then the forming roll units 7 will operate. The structure for operating the valves is indicated best in Figs. 1, 2, and 8. It comprises a transverse shaft 73 mounted in bearing brackets 74 secured to a baseplate 75 which is located adjacent the front of the machine. The ends of this shaft 73 carry the crank disks 76 which are keyed thereon. Connected to each disk 76 is a pitman 78 which is also connected to the operating lever 77 of the adjacent valve. The pitmans 78, associated with the valves 31 and 64, are connected to the disks 76 at points substantially 180° apart. Thus, the valves will be actuated at different intervals.

To rotate shaft 73 to operate the valves, I provide a foot lever 79 which has its rear end pivoted at 80 (Fig. 2) to a suitable support 81. An arm 82 extends upwardly from support 81 and carries a spring 83 which is connected to lever 79 and aids in pulling it to its uppermost position. The forward end of the lever 79 is associated with a ratchet wheel 84 (Fig. 8) which is keyed on shaft 73. The wheel 84 is provided with a grooved portion in which a chain 85 is disposed. The chain has one end connected to lever 79, as at 86, and the other end connected to a ratchet arm 87 pivotally carried by shaft 73. The arm 87 carries a pawl 88 which engages the ratchet teeth 89. A spring 90, connected to the outer end of arm 87 and to the baseplate 75, normally swings the arm 87 downwardly and lifts lever 79 upwardly into contact with shaft 73.

By pressing downwardly on the forward end of lever 79, the arm 87 is swung upwardly by the pull of the chain 85 and, since the pawl 88 engages ratchet teeth 89, the ratchet wheel 84 is rotated and, consequently, shaft 73 is rotated. As soon as pressure on the lever 79 is released, the spring 90 returns ratchet arm 87 and lever 79 to their original positions shown in Fig. 8. Thus, the shaft 73 may be rotated step-by-step to properly actuate the valves 31 and 64.

It will be apparent that I have provided a simple machine which is particularly effective for bending the ends of a pan blank to form the proper endwalls and to straighten out the resulting corner tab. However, my machine is not limited to such use.

The invention described herein may be manufactured and used by or for the Government of the United States of America for Government purposes without the payment of any royalty thereon or therefor.

What I claim is:

1. A forming machine for forming a blank of sheet metal having a wall previously formed

thereon, comprising a supporting structure, a metal brake pivotally attached to said supporting structure for bending the edge of the blank to form another wall adjacent the first and at an angle thereto and to simultaneously produce a tab extending diagonally outwardly from the corner thus formed, and a forming roll movably attached to said supporting structure and disposed adjacent said metal brake for engaging said tab and bending it to lie in the plane of 10 said first wall and to extend therefrom.

2. A forming machine for forming a blank of sheet metal of rectangular form having walls previously formed along opposite edges thereof, comprising a metal brake for engaging one of the other edges of the blank and bending it to form a wall substantially at right angles to the first walls and to simultaneously produce a tab at each of the two corners thus formed which extends diagonally outwardly, and movable forming rolls disposed at opposite sides of the metal brake for engaging the two tabs and bending them to lie substantially in the planes of said first-mentioned walls and to extend therefrom.

3. A forming machine for forming a blank of sheet metal of rectangular form having walls previously formed along opposite edges thereof, comprising a metal brake having relatively movable forming members for receiving one of the other edges of the blank and bending it to form a wall substantially at right angles to the first walls and to simultaneously produce a tab at each of the two corners thus formed which extends diagonally outwardly, one of the forming members of the brake having forming sections on its ends, and forming rolls disposed at opposite sides of the metal brake and movable into cooperative relationship with said forming sections to bend the tabs into contact therewith.

4. A forming machine according to claim 3 including tracks for guiding said rolls from positions laterally outwardly of the brake to positions where the rolls cooperate with said sections.

5. A forming machine according to claim 3 including forming roll supports which are adjustable to tilt the axes of said rolls at the desired angle.

6. A forming machine comprising in combination with a supporting table, a support for supporting the article to be formed, said support including forming sections at opposite sides thereof, forming rolls for bending portions of the article into contact with said sections and being disposed adjacent opposite sides of said support, supporting structures for said rolls, an operating rod connected to each of said supporting structures for imparting the desired movement to the rolls, tracks for guiding the movement of said rolls supporting brackets movably attached to said supporting table for carrying said tracks, and means for tilting said brackets and said roll supporting structures to tilt the axes of said rolls.

7. A structure according to claim 6 wherein said roll-supporting structures are adjustable laterally relative to each other and said track-supporting brackets are adjustable laterally relative to each other.

8. A structure according to claim 6 wherein said operating rods are reciprocably mounted in bearing sleeves, said sleeves being laterally adjustable, and said roll-supporting structures and 25 said track-supporting brackets being laterally adjustable.

9. A structure according to claim 6 wherein said roll supporting structures include arms mounted for swinging movement relative to the tracks, 30 and spring associated with said arms for causing the rolls to resiliently engage the tracks.
